Edwin S. Clarkson.

Inventor,

Robert Irons. Skiles,
By his Attorney, F. W. Ritter Jr.

UNITED STATES PATENT OFFICE.

ROBERT IRONS SKILES, OF DENVER, COLORADO, ASSIGNOR TO MARION WYRICK AND E. H. BOWMAN, JR., OF ROCK ISLAND, ILLINOIS.

DRAFT DEVICE FOR WAGONS.

SPECIFICATION forming part of Letters Patent No. 391,091, dated October 16, 1888.

Application filed March 22, 1887. Renewed August 6, 1888. Serial No. 282,081. (No model.)

To all whom it may concern:

Be it known that I, ROBERT IRONS SKILES, a citizen of the United States, residing at Denver, in the county of Arapahoe and State of Colorado, have invented certain new and useful Improvements in Draft Devices for Wagons, Cars, and other Vehicles; and I hereby declare the following to be a full, clear, and exact description of the same, reference being had to the accompanying drawings, wherein—

Figure 1 is a bottom or under side view of a tongue, axle, &c., having devices embodying my invention applied thereto. Fig. 2 is a longitudinal vertical section of a portion of a tongue and said draft devices. Fig. 3 is a transverse section of the same on the line *x x* of Fig. 2. Fig. 4 is a transverse section on the line *y y* of Fig. 2. Fig. 5 is a detached view of the buffer-box. Fig. 6 is a detached view of the combined slide, hook, and piston or follower; Fig. 7, a detached view of the two eyebolts of the axle through which the draft-chains pass. Fig. 8 is a sectional view on the line *z z*, Fig. 1, showing the connection of the draft-chains with the axle below the center of the axle.

Like letters and figures refer to like parts wherever they occur.

My invention relates to the construction and combination of draft devices for wagons, cars, and other vehicles, and has for its objects to help the horses in starting heavy loads, relieve them from sudden strains and shocks, and to permit the collars to set to the shoulder before the dead-weight of the pull is brought on the team.

To this end it consists in the peculiar combination of the tongue, a sliding doubletree, a buffer therefor, and equalizing draft-chains which extend from the doubletree loosely through eyes attached to the axle, all as will be hereinafter more specifically pointed out and claimed.

I will now proceed to describe my invention more specifically, so that others skilled in the art to which it appertains may apply the same.

In the drawings, A indicates the axle of a vehicle, B the fore-axle hounds, C the tongue-hounds, D the tongue, and E the tongue-bolt, all of which may be of the usual character, as shown, or any other approved construction.

1 indicates a buffer-box or spring cylinder, which is secured to the under side of the tongue D by bolts 2, or in any other suitable manner, the front end of the cylinder being closed by 55 a lug, (or head,) 3. (See Figs. 2 and 5.) Within the box 1 is a buffer-spring, 4, of any suitable character.

Arranged in line with buffer-box 1, and in rear thereof, is a slide-box, 5, which is secured 60 to the tongue D by bolts 6. Said slide-box is provided with grooves 7, (see Fig. 4,) in which moves the slide 8. The slide 8 (see Fig. 6) has at its front end a piston or follower, 9, which fits in the cylinder or bore of 65 the buffer-box 1, and bears on the buffer-spring 4, and is provided at its rear end with one or more draft-hooks, 10, (preferably two, as shown,) which engage with the draft-chain.

Pendent from the slide 8, between the draft-hooks 10, is the pivot-bolt or wagon-hammer 12 of the doubletree 13, said doubletree being pivoted on and movable with the slide 8.

14 indicates the draft-chain, which, if desired, may be made up of rod-and-link sections, as shown in Fig. 1. Its two ends 15 are secured to the opposite ends of the doubletree 13, the chain extending thence backward through the eyes or rings 16 of axle-bolts 17, and the middle of the draft-chain, as at 18, is 80 hooked over the draft-hooks 10 of the slide 8.

In order to obtain an upward or lifting pull on the axle A, the axle-bolts 17, having eyes or rings 16, are placed below the center of the axle, as clearly shown in Fig. 8. As the movement of slide 8 and doubletree 13 must take up the slack of draft-chain 14, so as to ultimately bring the draft or pull directly from the doubletree on the axle, it is evident that the length of draft-chain 14 must be proportioned to the 90 movement desired in slide 8 and piston or follower 9, and the parts can be relatively proportioned, so as to get any desired slack in the draft-chain 14, (say one, two, three, or four inches) when the team is at rest, and as a consequence the more or less gradual application of the power when the team is started.

The draft devices, being of substantially the character hereinbefore specified, will operate as follows: When the team is at rest, the buffer-spring 4 is expanded, the doubletree 13 and slide 8 are pushed back; and the draft-chain

14 is slack. The same condition exists in going downgrade. If, now, the team is started, the doubletree 13, slide 8, and piston 9 are drawn forward, the piston compresses the 5 buffer-spring 4, and the power is first applied gradually to the tongue and thence toward the load, so as to fully control and steady the tongue and prevent its wabbling and annoying the team. During this interval the collars have 10 time to tighten and set on the shoulders of the team before the dead-weight is taken up. As the doubletree 13 and slide 8 advance, the slack of the draft-chain 14 is taken up from the three points—namely, the two ends of the 15 doubletree and the slide hooks 10, or middle of the draft-chain 18—and the power is applied to the fore axle at two points, 16, below the horizontal central line of axle A.

Among the advantages of this construction 20 are the full control of the tongue and relief to the team from shocks, jars, and the sudden dead-weight of the load, all of which results from the first application of the power to the tongue and buffer, and next the advantageous 25 application of the power of the team thereafter, which results from the transfer of the force or final pull from the tonguedirectly to the axle, which occurs when the doubletree and slide 8 have moved sufficiently far to take up 30 the slack in the draft-chain 14.

Having thus described the preferred construction, as well as the operation and advantages of my invention, what I claim, and desire to secure by Letters Patent, is—

1. The combination, with the tongue, of a 35 buffer-box, a buffer-spring arranged in the box, a slide-box, a slide provided with a piston which enters the buffer-box and with hooks for attaching the draft-chains, and a doubletree pivoted on the slide, substantially 40 as and for the purposes specified.

2. The combination, with the fore axle and tongue, of a buffer-box secured to the tongue, a buffer-spring arranged therein, a slide-box secured to the tongue, a slide arranged in the 45 slide-box and provided with a follower and a draft-hook, a doubletree pivoted on the slide, and a draft-chain which extends from the doubletree through eyes or rings on the fore axle, substantially as and for the purposes 50 specified.

3. The combination, with the tongue, of a buffer-box, 1, slide-box 5, buffer-spring 4, and slide 8, having piston 9 and hooks 10, a doubletree pivoted on the slide 8, and draft-chain 14, 55 which extends loosely through the eyes or rings 16 of the axle and is attached to the doubletree at the three points, substantially as and for the purposes specified.

In testimony whereof I affix my signature, in 60 presence of two witnesses, this 9th day of March, 1887.

ROBERT IRONS SKILES.
